UNITED STATES PATENT OFFICE.

JONATHAN LUCAS, OF SAVANNAH, GEORGIA, ASSIGNOR TO LUCAS-LAMBORN-LOOM CORPORATION, OF NEW YORK, N. Y., A CORPORATION OF NEW YORK.

LOOM.

Application filed September 18, 1926. Serial No. 136,257.

My invention relates to looms and has for its object to provide a simple and novel beater mechanism whereby the operation of the beater is rendered more reliable and efficient than in existing constructions. Other more specific objects will appear from the description hereinafter and the features of novelty will be pointed out in the claims.

In the accompanying drawings, which illustrate an example of the invention without defining its limits, Fig. 1 is a sectional elevation of as much of the loom as is necessary to illustrate the novel mechanism; Fig. 2 is a front elevation thereof with parts in section, and Fig. 3 is a plan view.

As shown in the drawings, the customary reed 10 is mounted in the reed cap 11 and bottom beam 12, for instance, as illustrated in Fig. 1; said reed cap 11 and bottom beam 12 extending between and being carried by side arms 13. The latter are supported by means of rollers 14, arranged to travel in guide ways 15, fixed at the proper points upon the loom frame 16; the opposite ends 25 of the side arms 13, are pivotally connected at 17, with beater cams 18, pivoted at 19 upon the loom frame 16, as shown in Fig. 1. The beater cams 18 are constructed in the form of levers each of which is provided 30 with a cam slot 20, consisting of adjacent and continuing portions *a*, *b* and *c*, the purpose and operation of which will appear more fully hereinafter. The cam slots 20 each accommodate a cam roller 21 journalled 35 on the free ends of rocker arms 22, fulcrumed at 23 upon the frame 16; the rocker arms 22 are oscillated in the manner to be more fully set forth hereinafter by means of pitmen 24, each of which is pivotally connected at 25 with a rocker arm 22, and at 26 with a crank disc 27, mounted upon a 40 shaft 28, journalled in suitable bearings; it will be understood that the shaft 28 is mechanically actuated through the medium of 45 any suitable mechanism.

As the discs 27 are rotated, for instance, in the direction of the arrow in Fig. 1, an upward thrust will be imparted to the pitmen 24, which in turn will pivotally swing the rocker arms 22 in an upward direction and thereby cause the rollers 21 to travel upwardly in the cam slots 20. The continued rotation of the discs 27 finally causes the rocker arms 22 to be rocked downwardly 55 and the rollers 21 to travel toward the lower

ends of the cam slots 20. As the rollers 21 travel upwardly, for instance, from the position shown in Fig. 1, the sections *b* of the slots 20 will be traversed thereby, and will, accordingly, swing the cam levers 18 toward the left in Fig. 1. This movement will be communicated to the side arms 13 and thereby cause the supporting rollers 14 to travel lengthwise of the guideways 15 toward the front of the loom. As the rollers 21 continue their upward travel in the cam slots 20, they will enter the parts *c* thereof to complete the forward swinging of the cam levers 18. The reed 10 will partake of the movement of the side arms 13 and, accordingly, will ride forwardly and pack the filler threads in the conventional manner, it being understood that the warp threads pass through the reed in the well known way. As the rollers 21 begin their travel in the slots 20, in the reversed direction, the cam levers 18 will, accordingly, be pivotally moved toward the right in Fig. 1 and will impart a corresponding movement to the side arms 13 and thereby return the reed 10 to the position shown in Fig. 1. As the downward movement of the cam rollers 21 continues beyond the point illustrated in Fig. 1, said rollers 21 will traverse the sections *a* of the cam slots 20; as the curves of these portions *a* represent arcs of circles having the pivots 23 as centers the movement of the rollers 21 in the portions *a* of the slots 20, will cause no pivotal movement of the cam levers 18; the same is true when the rollers 21 travel from the lower ends of the slots 20 to the position shown in Fig. 1. In other words the period of time required by the rollers to move downwardly from the position shown in Fig. 1, to an extreme lowermost position and back again, may be referred to as a dwell during which the cam levers 18, the side arms 13, and consequently the reed 10, remain at rest. It will be noted that the threads or yarn pass from the customary warp beam 29 and that the woven material passes over the customary breast beam 30 to the take-up roll in the usual manner.

With the improved beater arm mechanism, 105 the reed is reciprocated in a horizontal direction toward and away from the packing position, whereby the packing of the filler threads is accomplished with a maximum of efficiency and in a uniform manner. The 110

mechanism illustrated and described whereby the horizontal reciprocation of the reed is accomplished, is reduced to the utmost simplicity and causes the reed to describe rapid movements toward and from the packing position and to occupy a position of rest in order to permit the filler threads to be laid by the shuttle. It will, of course, be understood that the devices herein shown and described, are constructed and arranged to operate in proper synchronism with the remaining mechanism of the loom which may be of any conventional type.

Various changes in the specific form shown and described may be made within the scope of the claims without departing from the spirit of my invention.

I claim:

1. In a loom, horizontal guides, a reed, side arms carrying said reed, rollers movable in said horizontal guides and carrying said side arms, oscillating levers connected with said side arms and provided with cam slots, and mechanism cooperating with said cam slots to oscillate said cam levers and thereby reciprocate said side arms and reed in horizontal directions.
2. In a loom, horizontal guides, a reed,

side arms carrying said reed, supporting rollers movable in said horizontal guides and carrying said side arms, oscillating levers connected with said side arms and provided with cam slots, rocker arms, cam rollers carried by said rocker arms and arranged to traverse said cam slots and mechanism for actuating said rocker arms to shift said cam rollers lengthwise of said cam slots, whereby said side arms and reed are reciprocated in horizontal directions.

3. In a loom, horizontal guides, a reed, side arms carrying said reed, supporting rollers movable in said horizontal guides and carrying said side arms, oscillating levers connected with said side arms and provided with cam slots, rocker arms, cam rollers carried by said rocker arms and arranged to traverse said cam slots, rotatable crank discs, and pitmen pivotally connected with said discs and with said rocker arms arranged to actuate the latter to shift said rollers lengthwise of said cam slots whereby said side arms and reed are reciprocated in horizontal directions.

In testimony whereof, I have hereunto set my hand.

JONATHAN LUCAS.
